REVERSE PLATING MECHANISM AND PROCESS.

Application filed November 22, 1926. Serial No. 149,952.

This application is a continuation as to all common subject-matter of my co-pending application Serial No. 111,770 filed May 26, 1926.

5 This invention relates to improved means and process for effecting reverse plating, particularly in machines having independently operated needles.

In order that the principle of the invention may be readily understood, certain embodiments thereof are disclosed in the accompanying drawings, wherein—

10 Fig. 1 is a rear elevation of a circular knitting machine having the invention applied thereto;

15 Fig. 2 is a detail showing in rear elevation a portion of the mechanism of the invention;

20 Fig. 3 is a detail in side elevation viewing Fig. 2 from the left;

25 Fig. 4 is a similar detail but viewing Fig. 2 from the right;

30 Fig. 5 is a plan view representing the arrangement of cams and casting off mechanism in a machine of the character chosen for illustration;

35 Fig. 6 is a vertical central section of the structure shown in Fig. 5;

40 Fig. 7 is a plan view of the latch ring and of the cams to move the web holders and special instrumentalities;

45 Fig. 8 is an inside view of a part of the head of the knitting machine showing the web holders, special instrumentalities and needles;

50 Fig. 9 represents in side elevation eleven different positions of a special web holder and the adjacent needle in the formation of a reversely plated loop;

55 Fig. 9^a represents in side elevation a needle and the two plating yarns in successive positions in the formation of reverse plating;

60 Fig. 9^b is a perspective view of two of the special web holders showing contrasting length butts;

65 Fig. 10 is a view similar to Fig. 9, but representing in successive positions a regular web holder and adjacent needle in the formation of normal plating;

70 Fig. 10^a is a view similar to Fig. 9^a but representing the positions for normal plating; and

75 Fig. 11 is a plan upon an enlarged scale of certain of the web holders and special in-

strumentalities and the special cams for operating the same.

In Patent No. 1,605,895, dated November 2, 1926, means are disclosed for effecting reverse plating by the action of casting off 60 mechanism, and whereby striping is effected extending lengthwise the hosiery or other knitted article. In the present application, means are disclosed for effecting reverse plating through the action of special web 65 holders, and there is provided means for shifting or altering during the knitting operation the point or points at which the reverse plating is effected. In the disclosed embodiment of the invention the plating is 70 effected in lines, bands or blocks extending lengthwise the hosiery or other article. In said disclosed embodiment of the invention the reverse plating is accomplished through the action of specially shaped web holders, 75 or like instrumentalities, each of which is placed alone in a radial groove of the web holder sinker ring; and at the points or areas where normal plating is to occur, regular web holders or like instrumentalities are 80 provided.

This invention is radically contrasted with machines for making those fabrics wherein a lengthwise extending stripe is produced by floating one of the two plating yarns at predetermined times. In accordance with this invention the plating of the fabric throughout the whole or a predetermined extent thereof is effected in any usual manner, and at predetermined lengthwise extending 85 areas, a reversal of the plating operation is effected. That is, upon certain predetermined parts of the plated work, one of the threads is caused to appear upon the outer face of the fabric, and in other parts the other thread is caused to appear upon the said outer face thereof, thus securing lengthwise striping. Such striping may be characterized by continuous or long stripes, or by short or interrupted stripes, or various 90 combinations of continuous and interrupted stripes may be resorted to, as more fully described and as illustrated in said Patent No. 1,605,895.

Independent needles are employed, between which are positioned casting off instrumentalities herein shown as web holders, and when no vertical striping is to be effected, all said web holders or instrumentalities act in what may be termed a normal 105

manner, so that what may be termed normal plating results. Certain of said web holders or instrumentalities are, however, of peculiar formation, and when reverse plating 5 is to be produced, such web holders or instrumentalities of special formation are projected inward at an earlier point circumferentially considered, so as to engage the yarn which was the back yarn during normal 10 plating, and so to position the same that it becomes the face or front yarn. By the employment of suitable means, preferably automatic, the normal plating may be interrupted at any point, and reverse plating may 15 be effected at any desired wale or wales and continued for as few or for as many courses as desired, then to be replaced by normal plating.

Such normal and reverse plating are effected without any change in the relative 20 tension of the two yarns and no measuring of the yarn is effected in the formation of the loops, as is characteristic of full fashioned machines.

25 The machine, herein shown as one upon which the invention may be practiced, need not be specially described inasmuch as it is shown as the well known Banner or Hemp-hill machine. Briefly, it is to be noted that 30 the machine is of the independent needle type and that the needles are desirably latch needles. Therefore, there is provided upon a suitable framework 1, as upon a standard 35 2 rising from the bed plate 3 thereof, a latch ring 4 equipped with suitable binder mechanism generally indicated at 5, and operatively connected to link and lever mechanism 6 controlled from the pattern drum 7 upon the pattern drum shaft 8. The entire mechanism 40 is driven from the main shaft 9 having thereon the usual pulleys 10 and also the usual gearing for imparting rotary and reciprocating movements in a well known manner. The mechanism is also provided 45 with the usual narrowing pickers and the usual widening pickers, one each of which is indicated at 11, 12, respectively. These pickers are desirably those of the said Banner machine and require no further description.

50 The needle cylinder is indicated at 13 and within the grooves thereof are received the independently operated latch needles 14. At the upper end of the needle cylinder is provided the web holder receiving and operating mechanism which is generally similar to that of the Banner machine, but altered in accordance with the invention. The web holder bed ring is herein shown at 15. Positioned thereabove is 55 the sinker cam ring 16, shown most clearly in Figs. 5 and 6. The web holder bed ring is provided with the usual radial grooves within which are located at the points where normal plating is always to occur, web 60 holders or like instrumentalities 17 of usual

construction, such, for instance, as indicated as positioned at desired points among the special web holders in Figs. 8, 11, and elsewhere.

Viewing Fig. 2, it will be observed that 70 there are provided substantially as usual the brackets 18, 19 which cooperate with the stationary upstanding bracket 2 in suitable positioning the sinker or web holder cam ring for reciprocating knitting. 75

There is provided certain operating mechanism for so positioning the special web holders as to move the same radially inward at an earlier point, as hereinbefore referred to, and herein for the purpose two levers 80 are provided which act upon said specially shaped web holders which for the purpose of lever actuation are made of two contrasting shapes at their outer ends or butts so as to permit each lever to act only upon the 85 special web holders pertaining thereto, and arranged singly or in groups as desired throughout the circle of needles; and desirably these two or other desired number of levers are mounted and positioned in a 90 manner similar to that shown in said Patent No. 1,605,895, although this invention is not limited to such arrangement.

The regular web holders, as already stated, are indicated at 17, and they are provided with the usual butts 17' or tails so as to be acted upon by the stationary web holder cams most clearly indicated in Fig. 5 at 20, 21, 22, 23. They may be varied in form in accordance with operating conditions, and the invention is in no wise limited to the particular form thereof shown. Each such web holder (within which definition is included the so-called sinker) is mounted for in and out or radial sliding movement in 100 a groove of the web holder bed ring 15, and in other radial grooves of said bed ring and distributed in such grooves as desired (but in no case in the same groove as a regular web holder, though this invention is not necessarily limited in this respect) are provided the web holders of special form which will be referred to more fully hereinafter.

Referring merely for purposes of consecutive description to the form of special web holder or instrumentality herein shown and claimed, namely, that form shown in Fig. 9, it is to be noted that said specially formed web holder or special instrumentality is indicated at 24, and is provided with a tail or butt 25 upstanding therefrom. Although there is shown in said figure but one height or length of tail or butt 25, it is to be understood that when employing two operating levers, contrastingly formed tails or butts are provided, which desirably distinguish from each other in height.

Said special form of web holder or instrumentality 24 which is particularly 120

adapted to a coarser yarn or a yarn of intermediate size, but which use is obviously not limited to employment with such yarns, is provided with a vertical edge 26 extending to substantially the height shown in Fig. 9 and elsewhere, at which point an upwardly and rearwardly inclined edge 27 is provided, terminating in a point 28 beyond which is a curved edge 29 merging into the downwardly extending vertical edge 30. Below the vertical edge 26 is a relatively shallow but relatively wide notch or recess 30'.

The action of this special form of web holder in reverse plating will be fully described at a subsequent point.

Radially outside of the cam point 22 of the sinker cam ring and at such a point as to engage the outer end portion or butt 25 or the like of the special web holders, are provided two levers 31, 32 pivoted at 33 upon a suitable bracket or part of the machine, herein the web holder cam ring. The short ends 31', 32' of said levers are actively engaged by springs 31'', 32'' tending normally to force the opposite or functioning end of said levers outwardly. The inner or opposite end of said levers 31, 32 are here shown as having cam formations or faces 30 which are normally moved out of functioning relation or position into outer or non-functioning position (that is, for normal plating) by means of said springs 31'', 32'', it being understood that the function of said cam formations is to move the special web holders inward so as to cause them to push the back thread of normal plating into position to be the face thread of reverse plating. There are provided means preferably acting automatically to move the longer ends of said levers 31, 32 inwardly, and for that purpose there is shown the following mechanism, to which this invention is in no wise restricted and which may be and desirably is substantially the same as that shown in said patent.

As most clearly shown in Figs. 2, 3 and 4, a bracket or standard 34 is provided in which are mounted for sliding movement two bars 35, 36 of which the overlying or upper bar strikes a suitable pin 37 (see Fig. 5) upon the overlying cam lever 32 and the lower bar 36 strikes a pin 38 upon the underlying cam lever 31. Thus at times determined by the respective controlling means for the said bars, one or the other of the said cams 31, 32 is moved radially inward sufficiently for it to cause the special web holders controlled by it to engage the back yarn and effect reverse plating in a manner already referred to.

Each bar 35, 36 is connected by a pin, one of which is indicated at 39 in Fig. 5 to the proper lever 40, 41, pivoted at 42 upon the framing of the machine so as to be

swung in a horizontal plane at the proper time. Said levers, which are also indicated generally in Fig. 1, are notched or suitably formed at their outer ends to be engaged by the ends 43, 44 of bell crank levers pivoted at 45 upon the bracket 34, and are respectively connected at 46, 47 to downwardly extending links 48, 49 which, as shown in Fig. 1 extend downward to controlling pattern disks or members 50, 51 upon the pattern shaft 8. Said disks or members 50, 51 are of proper shape to impart the in and out movement to said cam levers 43, 44, at the predetermined time so as in the operation of the mechanism to cause reverse plating to occur whenever either of said levers 43, 44, or both of them, is or are moved inwardly. If the article being knitted is a hose or stocking the said disk members 50, 51 are desirably so shaped as to cause reverse plating to cease during heel and toe work, and at that time a special heel and toe yarn is or may be introduced.

In Figs. 7 and 8 is represented in elevation the feeding of two yarns in plating relation, namely, the black yarn 52, which in normal plating is the back yarn, and the white yarn 53, which in normal plating is the face yarn. These two yarns are supplied through corresponding yarn guides 52', 53', mounted in the usual manner with the group of yarn guides of the Banner machine so as to enter the throat thereof in a well understood manner. In proper relation to the said yarn guides or needles are positioned the knitting cams, not herein shown, but which are desirably of the usual type in the Banner machine.

Desirably the regular web holders are provided with short upwardly extending butts, and the special web holders interspersed thereamong or arranged as desired to provide the predetermined pattern, are provided with longer butts, and said longer butts are contrastingly shaped among themselves so as to cooperate respectively with the cam portions of the levers 31, 32.

Referring now to that form of special web holder shown in Figs. 9 and 11, it is to be understood that the butt 25 thereof is to be operated upon by the regular fixed cams 20, 21, 22, 23 of the web holder cam ring so long as said special web holders act in forming normal plating, but when they are to be pushed in at an earlier point circumferentially considered, as indicated in Fig. 5, they are then acted upon by the cam portion of whichever lever 31, 32 is apportioned thereto. In other words, if the butts or heels 25 of these special web holders are medium and long respectively, then the medium length butts are acted upon by the lower cam lever 31 and the longer butts are operated on by the upper lever 32. Within the scope of my invention but a single lever 31 or 32 or a

single instrumentality for the purpose may act upon all the special web holders, this being determined in accordance with the simplicity or complexity of the pattern.

- 5 If a stocking without the vertical striping is desired, that is, if solid, or what may herein be termed normal plating, is to be provided, all of the web holders including the special web holders, are moved inwardly 10 to the same radial extent and function as usual web holders. If, however, vertical striping is to be provided, one or more of the special web holders, according to the pattern desired, is or are moved inward at an earlier period by means of the proper cam lever 31, 32, so as to cause each of said special web holders that is to function in the creation of reverse plating to engage the black yarn 52, which in normal plating is 20 the back yarn, so as to move the same inwardly in advance of the white yarn 53 which had appeared at the front in normal plating. The result is to produce stripes of a width determined by the number of consecutive special web holders, and of a length dependent upon the length of time the cam lever 31 or 32 is in its inner radial position, and which in turn is dependent upon the pattern control.
- 25 Reference is made at certain points in the preceding portion of the specification to the effect that the special web holders or instrumentalities engage the yarn which was the back yarn during normal plating, and so 30 position the same that it becomes the face or front yarn, but such reference is not intended to be inconsistent with statements elsewhere made that said special instrumentalities at certain times engage both the yarns, the first mentioned statement being particularly concerned with the said back yarn and 35 not being intended as a statement directed wholly or exclusively to said back yarn.
- 40

Viewing Figs. 8 and 11, it is to be understood that the yarn shown at 52, being more to the left in each of said figures, is fed without tension and that the yarn 53 is tensioned as by tension disks, such as shown in said patent. It will also be observed that 45 the yarn 53 which in normal plating appears at the front or outer face of the fabric is introduced slightly in advance circumferentially of the yarn 52. The tension upon the 50 yarn 53 is maintained at all times when normal or reverse plating is being effected.

55 It will be understood that in plating, the yarn to the front of the needles is the one which appears on the back (inside) of the finished stocking or other article. In normal plating, this is the yarn which in the preferred practice of the invention is without tension, and the other yarn which in the preferred practice of this invention is under tension appears on the outside or face of 60 the finished stocking or other article.

In normal plating, the front yarn, which in the disclosed embodiment of the invention is under tension, strikes the needles more quickly, and lower down on the stems thereof, than does the back yarn, but the back 70 yarn first engages the needles higher up and it may be in the hooks thereof. The said front yarn, as, for example, the yarn 53, will get up into the hook of each needle last, and will in normal plating tend to act as a wedge 75 to force the back yarn toward the front of the hook of the needle.

In reverse plating, there is no change in the tension of the tensioned yarn, herein the front yarn, and the other yarn is still permitted to be fed without tension, but the action of the special web holders or instrumentalities is, with the other cooperating parts, such as to effect a reversal in the position of the two yarns. In normal plating as 80 each needle takes the threads and draws them down over the shoulders of the web holders, both threads crowd against the shanks of one or more of the needles immediately behind the rearmost needle which is 85 just pulling the thread over a web holder shoulder. This crowding action is due to the fact that the needles are carried by the rotating needle cylinder, or in other words are revolving about the axis of the needle 90 cylinder, as will be understood from an inspection of Figs. 5, 6, etc., the needles taking the threads as they do ordinarily in a machine of the type shown. During normal plating the two threads, fed in the customary manner in a plating relation are drawn or crowded toward the outer side of the 95 needle cylinder, and the threads are maintained in this relationship while the needles continue to move downwardly and draw additional thread to form both needle and sinker loops of the length required in knitting. The maintenance of the threads in 100 this definite and predetermined relationship to each other during the loop forming operation is incidental to the feeding of the yarns in a plating relation and the drawing of the 105 said yarn by the needles as so fed. So long as the knitting operation proceeds in this manner a plated fabric will be produced 110 having a substantially white outer surface and a substantially black inner surface, the 115 fabric at the knitting point being inside out.

If, during the initial stages of the stitch forming operation, a special instrumentality 120 or device is pressed against the sides of the thread opposite to the shank of the needle hook, the threads can be reversed. For this purpose there is preferably employed a special instrumentality in the general nature of a web holder and functioning as such in the normal plating operation, and for this purpose the special web holders or instrumentalities are represented at 125 24. Such web holder or instrumentality has the 130

usual web supporting shoulder 54 like a regular web holder, and it has the work engaging face or edge 26 already referred to, which is here shown as vertical or extending parallel to the axis of the needle.

In the said parent application Serial No. 111,770, Fig. 13 shows four different positions of a special instrumentality and the adjacent needles, but without attempting to show all the positions for either normal plating or reverse plating during the downward or loop drawing movement of the needle. In said Fig. 13, the first two positions indicate reverse plating and the third and fourth positions indicate normal plating and are intended simply to show that form of special instrumentality and to indicate the use thereof.

In a standard gauge Banner machine of three and a half inch diameter, employing two hundred and forty needles in the needle circle, there are eleven needles counting from the needle in the lowermost position in Fig. 8 upward to the needle just preceding that which is in position to begin its downward movement. This actual structure is shown in Fig. 8 of this application.

In Fig. 9 are represented twelve positions of a needle and its special instrumentality, being the positions of the twelve needles just referred to and also the needle which has just commenced its subsequent upward movement. In other words, in Fig. 9 are represented eleven positions which are assumed by each needle that has associated therewith a special instrumentality, and also said instrumentality, it being understood that intermediate those positions are other positions slightly variant therefrom.

Referring to said Fig. 9, and also to Figs. 8 and 11, the relation of the two threads, the needle and the special instrumentality will be clear. In position No. 1 the needle 14 is at the upper level shown in Fig. 8 and the two threads 52, 53 are in proximity to the needle, the special web holder 24 not having yet commenced its inward movement. In the second position, said special web holder has not yet commenced its inward movement, but the needle has just begun its descent. In the third position, the special web holder or instrumentality has not yet commenced its inward movement, but the needle has moved slightly further downward. In the fourth position, the special instrumentality has been moved slightly inward by the special cam or cam lever 31 or 32 pertaining thereto, the needle has moved slightly further downward, and the two threads are in closer relation to the needle stem. In the fifth position, the special web holder has been moved inward slightly further, so that the lower or tensioned thread 53 has now been engaged by the edge or face 26 thereof, and the upper or

non-tensioned thread 52 has not as yet been engaged by said edge 26. In the sixth position, the special instrumentality 24 has been moved further inward, and, having its edge 26 in engagement with both threads 52, 53, is pushing both of them inward, the needle being now moved slightly further downward. In the seventh position, the special instrumentality 24 has been moved slightly further inward. Both threads 52, 53 are still in engagement with the edge 26, and are therefore being pushed inwardly, and the needle is being moved still further downward. In the eighth position, the special instrumentality 24 is in the same position as in the seventh position, and the tensioned thread 53 has now slipped off the lower edge of the face 26 into the recess 30', the non-tensioned thread 52 being still engaged by the edge or face 26, and it is thus brought into a position insuring its appearance at the outer face of the fabric. In other words, the position of said thread 52 is thus reversed from the position it occupies in normal plating. In the eighth position, the needle has moved slightly further downward. In the ninth position, the special instrumentality 24 is still in the same position, but the needle has moved slightly further downward, and both the yarns or threads 52, 53 are now within the recess 30', but in the relation to each other necessary for reverse plating. In the tenth and eleventh positions, the special instrumentality 24 has been moved slightly further in, but now by the regular cam, and the needle is moved slightly further downward. In the twelfth position, the needle has commenced to move upward and the special instrumentality 24 is still in the same radial position.

It will be understood from the foregoing description and from the illustration that the special web holders or instrumentalities engage the threads or yarns at an abnormally early point in the loop forming operation, and that the edge or face 26 of each special web holder or instrumentality 24 presses against a side of the two threads 52, 53 during the initial steps in the formation of the reversely plated loops.

It will be evident that the face or edge 26 of each special instrumentality 24 is moved into engagement with both the threads or yarns while the needles draw the threads downwardly toward the shoulders of the said special web holders, that is, toward the shoulder 54.

While I have in the specification generally used the term "special instrumentality" or "special web holder," it is to be understood that within this definition, a special sinker, so-called, is comprehended. It will also be understood that the so-called regular web holders may also be and in practice frequently are termed "sinkers," and that the

portions thereof overhanging the shoulders may be termed "beaks".

In the knitting operation, as the web holders, whether regular or special instrumentalities, approach the point in their orbits or points of rotation at which the needles take the thread, they are all forced outwardly by cam 21 (Fig. 5) in regular manner. After the needles have taken the threads and while they are drawing the bights of the threads down over the shoulders of the web holders, the regular web holders are forced inwardly by reason of the engagement of their butts 17' with the cam 22 (Figs. 5 and 11). One or the other of the movable or auxiliary cams or cam levers 31, 32, engage the butts 25 of the special instrumentalities 24 and force said special instrumentalities into engagement with the work at an earlier point in the stitch forming operation than do the regular web holders, as already stated. There is, as already stated, a differential tension established with respect to the two threads 52, 53, but in the practice of this invention, preferably there is tension applied to the lower thread 53, and the upper thread is fed substantially without tension. The feeding of the threads in the position indicated and the maintenance of the relative tension, which is maintained during both normal and reverse plating, preserves the described relationship of the two threads 52, 53, in normal plating while the needles continue to move downward and draw the thread in the loop forming operation.

In effecting reverse plating, the special instrumentalities 24 are moved in, as stated, at a relatively earlier period than are the regular web-holders, and this occurs during the initial stages of the stitch forming operation, with the result that during the initial stages of the stitch forming operation, both threads are engaged and are moved or pushed by the vertical face 26 or edge of each special instrumentality 24.

Having thus described one illustrative embodiment of the invention, it is to be understood that although specific terms are employed, they are used in a generic and descriptive sense, and not for purposes of limitation, the scope of the invention being set forth in the following claims:

1. That improvement in the process of knitting plated fabrics which consists in feeding two threads simultaneously to the knitting needles, maintaining a greater tension on one thread than the other during the feeding thereof, causing said needles to engage the threads to form loops in said threads, pressing against the threads laterally at one side thereof during the initial steps in the formation of normal loops, and reversing the relative positions of said threads in certain of the loops by pressing

against the opposite sides of the threads during the initial steps in the formation of the latter loops.

2. That improvement in the process of forming stripes in knitting plated fabrics which consists in feeding two threads simultaneously to a series of needles, causing said needles to draw said threads over a series of sinkers, and thereby form loops in the threads, maintaining a greater tension on one of said threads than the other during the feeding thereof and thereby maintaining the tensioned thread normally at one face of the knitted fabric, and reversing the threads at certain of the sinkers by causing the latter sinkers to engage the threads at an abnormally early point in the loop forming operation.

3. In a knitting machine, the combination with a series of needles and the usual sinkers cooperating with said needles, of means for feeding a plurality of threads simultaneously to said needles, means for maintaining a differential tension on said threads, devices interspersed with said sinkers for engaging and pushing against the threads between adjacent needles during the initial steps of the stitch forming operation, and means for moving said devices into engagement with the threads while the needles draw the threads downwardly toward the sinker shoulders.

4. In a knitting machine, the combination of a series of needles, sinkers cooperating with said needles, devices for feeding two threads simultaneously to said needles, means for maintaining a considerable tension on one of said threads while allowing the other thread to feed more freely, special sinkers interspersed with the first mentioned sinkers and having faces to engage and push against said threads, and sinker operating mechanism including means for moving the special sinkers against the threads held by the needles in advance of the other sinkers and while the needles are carrying said threads down to the shoulders of the special sinkers.

5. In a knitting machine, the combination of a series of needles, devices for feeding two threads simultaneously to said needles, means for maintaining a greater tension on one of said threads than the other, sinkers cooperating with all of said needles and including both sinkers of the usual type and also special sinkers located at points where vertical stripes are to be made in the fabric, said special sinkers having web supporting shoulders and also having parts above said shoulders for engaging the portions of the threads between the needles as the needles draw the threads down toward said shoulders, cams for operating all of said sinkers in the same time relationship to the movements of the needles, and an auxiliary cam

for operating the special sinkers when desired to cause them to engage the threads while the threads are being moved downwardly toward the sinker shoulders.

- 5 6. In a knitting machine, the combination of a series of needles, devices for feeding two threads simultaneously to said needles, means for maintaining a greater tension on one of said threads than the other, two sets 10 of sinkers cooperating with said needles and both having the usual shoulders over which the needles draw the loops of thread, one set of said sinkers being provided with the usual beaks overhanging said shoulders 15 and the second set of sinkers each having an upwardly directed thread engaging surface above the shoulder thereof to push laterally against the threads, the sinkers of said second set being located at points where 20 a vertical stripe is to be made in the fabric, cams for operating all of said sinkers in the same time relationship to the movement of the needles, an auxiliary cam for operating said second set of sinkers to cause them 25 to push laterally against the threads between the needles as the needles draw the threads downwardly toward the sinker shoulders, and means for throwing said auxiliary cam into or out of operation, as 30 desired.

7. In a circular knitting machine, the combination of a circular series of needles, means for feeding two threads simultaneously to the needles, means for maintaining 35 a greater tension on one thread than the other during the feeding thereof, means to cause said needles to engage the threads to form loops in said threads, the construction and arrangement of the parts causing both 40 threads to press at one side thereof against the shanks of one or more of the needles during the initial steps in the formation of normal loops, and means acting to reverse the relative positions of the said threads in 45 certain of the loops by pressing against the opposite sides of the threads during the initial steps in the formation of the reversely plated loops.

8. In a circular knitting machine, the combination of a circular series of needles, means for feeding two threads simultaneously to the needles, means for maintaining a greater tension on one thread than the other during the feeding thereof, means to cause said 55 needles to engage the threads to form loops in said threads, the construction and arrangement of the parts causing both threads to press at one side thereof against the shanks of one or more of the needles during 60 the initial steps in the formation of normal loops, and special instrumentalities interspersed between needles and movable transversely with respect thereto to reverse the relative positions of said threads in certain 65 of the loops by pressing against the

opposite sides of the threads during the initial steps in the formation of the reversely plated loops.

9. In a knitting machine, a series of needles and interspersed sinkers or web holders, 70 means for feeding two threads simultaneously to said series of needles, means for causing said needles to draw said threads over a series of said sinkers or web holders and thereby to form loops in the threads, 75 means for maintaining a greater tension on one of said threads than the other during the feeding thereof, and thereby maintaining the tensioned thread normally at one face of the knitted fabric, and means for reversing the threads at certain of the sinkers or web holders by causing said certain sinkers or web holders to engage the threads at an abnormally early point in the loop forming operation. 80

10. In a knitting machine, a series of needles, sinkers or web holders interspersed thereamong and movable transversely of the series of needles, special instrumentalities interspersed among certain of said needles and 85 also movable transversely with respect to the needle series, cam means to move said sinkers or web holders transversely of the needle series, means to feed two threads simultaneously to said needles while maintaining a greater tension on one of said threads than the other, and cam means to move said special instrumentalities transversely of the needle series at an earlier point with respect to said needle series than is done by the cam 90 means for the said sinkers or web holders, thereby effecting reversal of the threads at said special instrumentalities by causing the latter to engage the threads at an abnormally early point in the loop forming operation. 95

11. In a knitting machine, a series of needles, sinkers or web holders interspersed thereamong and movable transversely of the series of needles, special instrumentalities interspersed among certain of said needles and 100 also movable transversely with respect to the needle series, cam means to move said sinkers or web holders transversely of the needle series, means to feed two threads simultaneously to said needles while maintaining a greater tension on one of said threads than the other, said special instrumentalities having among themselves contrasting formations, and cam means acting 105 selectively to engage and move said special instrumentalities transversely of the needle series to engage the threads at an abnormally early point in the loop forming operation to effect reversal of the threads. 110

12. In a knitting machine, a series of needles, sinkers or web holders interspersed thereamong and movable transversely of the series of needles, special instrumentalities interspersed among certain of said needles and 115 also movable transversely with respect to the needle series, cam means to move said special instrumentalities transversely of the needle series to engage the threads at an abnormally early point in the loop forming operation to effect reversal of the threads. 120

13. In a knitting machine, a series of needles, sinkers or web holders interspersed thereamong and movable transversely of the series of needles, special instrumentalities interspersed among certain of said needles and 125 also movable transversely with respect to the needle series, cam means to move said special instrumentalities transversely of the needle series to engage the threads at an abnormally early point in the loop forming operation to effect reversal of the threads. 130

to the needle series, cam means to move said sinkers or web holders transversely of the needle series, means to feed two threads simultaneously to said needles while maintaining a greater tension on one of said threads than the other, said special instrumentalities having among themselves different length butts and a plurality of cams positioned to engage said butts according to

their lengths and selectively to move said special instrumentalities transversely of the needle series, so as to engage the threads at an abnormally early point in the loop forming operation and effect reversal of said threads at said special instrumentalities.

In testimony whereof, I have signed my name to this specification.

ROBERT H. LAWSON.
